Primary Examiner — Carla J Wright

(57) **CLAIM**

The ornamental design for a phone case set, as shown and described.

DESCRIPTION

FIG. 1 is a first perspective view of two elements of a phone case set showing my new design;

FIG. 2 is a second perspective view of the two elements thereof;

FIG. 3 is a front view of the two elements thereof;

FIG. 4 is a back view of the two elements thereof;

FIG. 5 is a left side view of the two elements thereof;

FIG. 6 is a right side view of the two elements thereof;

FIG. 7 is a top view of the two elements thereof;

FIG. 8 is a bottom view of the two elements thereof; and,

FIG. 9 is a perspective view in which the two elements of the phone case set are shown in an assembled state.

1 Claim, 9 Drawing Sheets
